UNITED STATES PATENT OFFICE.

JOHN H. STAPP, OF SAN FRANCISCO, CALIFORNIA.

DESIGN FOR A COIN BANK.

Application filed May 31, 1927. Serial No. 22,244. Term of patent 14 years.

To all whom it may concern:

Be it known that I, JOHN H. STAPP, a citizen of the United States, residing at the city and county of San Francisco and State of California, have invented a new, original, and ornamental Design for a Coin Bank, of which the following is a specification, reference being had to the accompanying drawing, forming part thereof.

The drawing is a perspective view of my coin bank showing my new design.

I claim:

The ornamental design for a coin bank as shown.

JOHN H. STAPP.
